(57) **CLAIM**

The ornamental design for the virtual reality 3D glasses, as shown and described.

DESCRIPTION

FIG. 1 is a front elevational view of the virtual reality 3D glasses showing my new design in an unfolded condition; FIG. 2 is a rear elevational view thereof; FIG. 3 is a left side view thereof; FIG. 4 is a right side view thereof; FIG. 5 is a top plan view thereof; FIG. 6 is a bottom plan view thereof; FIG. 7 is a perspective view thereof; FIG. 8 is a front elevational view of the virtual reality 3D glasses shown in FIG. 1, wherein the virtual reality 3D glasses are in a folded condition; FIG. 9 is a rear elevational view thereof; FIG. 10 is a left side view thereof; FIG. 11 is a right side view thereof; FIG. 12 is a top plan view thereof; FIG. 13 is a bottom plan view thereof; FIG. 14 is a perspective view thereof; FIG. 15 is another perspective view thereof; FIG. 16 is a front elevational view of the virtual reality 3D glasses folded and housed in a case; FIG. 17 is a rear elevational view thereof; FIG. 18 is a left side view thereof; FIG. 19 is a right side view thereof; FIG. 20 is a top plan view thereof; FIG. 21 is a bottom plan view thereof; FIG. 22 is a perspective view thereof; FIG. 23 is another perspective view thereof; FIG. 24 is a front elevational view of the case; FIG. 25 is a rear elevational view thereof; FIG. 26 is a left side view thereof; FIG. 27 is a right side view thereof; FIG. 28 is a top plan view thereof; FIG. 29 is a bottom plan view thereof; FIG. 30 is a perspective view thereof; and, FIG. 31 is another perspective view thereof.
